(57) **CLAIM**

I claim the ornamental design for a display screen or portion thereof with transitional graphical user interface, as shown and described.

DESCRIPTION

FIG. 1 is the first image in a sequence for a display screen or portion thereof with transitional graphical user interface showing my new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof; and,

FIG. 11 is the eleventh image thereof.

The outer perimeter broken lines in the drawings represent a display screen or portion thereof and form no part of the claimed design. The remaining broken lines in the drawings illustrate portions of the transitional graphical user interface that form no part of the claimed design.

The appearance of the transitional image sequentially transitions between the images shown in FIGS. 1 through 11. The process or period in which one image transitions to another image forms no part of the claimed design.
